UNITED STATES PATENT OFFICE.

ALLAN J. CLINE, OF CHICAGO, ILLINOIS.

WEB-ROLL STAND.

Application filed November 29, 1920. Serial No. 427,161.

To all whom it may concern:

Be it known that I, ALLAN J. CLINE, a citizen of the United States, and a resident of Chicago, in the county of Cook and State 5 of Illinois, have invented certain new and useful Improvements in Web-Roll Stands, of which the following is a specification, reference being had to the accompanying drawings.

10 My invention relates to stands or reels for supporting a plurality of rolls of web so that they can be conveniently supplied to a printing press or other machine through which the web is to be conducted for further operations. In feeding webs to printing presses particularly, it is necessary at times to adjust the roll longitudinally of itself, or transversely to the path of the web, as it is unreeled, to secure the proper marginal 15 alinement. Heretofore, where roll stands and a plurality of rolls have been employed the roll supports have been mounted on a rotary shaft journaled in bearings carried by standards, and the desired marginal adjustment has been obtained by making one 20 of the standards adjustable in such manner that by moving it laterally the shaft with the roll supports carried by it would be adjusted endwise. This construction, however, is unsatisfactory, and the object of my invention 25 is to provide improved means for attaining the same end. I accomplish my object as illustrated in the drawings and hereinafter described. What I regard as new is set 30 forth in the claims.

In the accompanying drawings,—

Fig. 1 is an end view of a roll stand embodying my improvements, some parts being broken away; and

40 Fig. 2 is a partial sectional view showing the details of my improved construction.

As shown in the drawings, my improved stand comprises a roll support carrying shaft 3, one end of which is mounted in an 45 ordinary bearing carried by a standard which is not shown, as it may be an ordinary fixed standard of any suitable description, and the bearing may be of any approved construction which will permit endwise

movement of the shaft 3 through it. A 50 standard suitable for this purpose, is, however, shown in my application of even date herewith for improvements in paper roll chucks. The opposite end of the shaft 3 is mounted in a suitable bearing 4 carried by 55 a standard 5, as shown in detail in Fig. 2. The shaft is not mounted directly in said bearing, but is fitted into the hub 6 of a worm wheel 7 in such manner that it may move longitudinally therein, but rotates therewith. 60 This is best accomplished by a key 8 interposed between the hub 6 and the shaft 3, as shown in said figure. The hub 6 has no longitudinal movement in the bearing 4, but on the contrary is held against such 65 movement by an annular plate 9 which is secured to the outer end of the hub 6 by screws 10, and overlaps the margin of the bearing 4, as shown. By this construction the shaft 3 is free to move endwise through 70 the hub 6.

The worm wheel 7 is provided for the purpose of rotating the shaft 3 to move one or another of the rolls carried by it into position for use, such rolls being mounted between a pair of roll supports 11 having spindles or chucks 12 which engage the opposite ends of the usual mandrel which forms the core of a roll. Usually the roll supports 11 are equipped to carry three 80 rolls arranged equally distant apart so that by rotating the shaft 3 any one of the rolls can be moved into or out of operative position. The worm wheel 7 is arranged to be rotated by a motor 13 mounted on a bracket 85 14 carried by the standard 5, as shown in the drawings. This motor is operatively connected with the worm wheel 7 by a pinion 15 mounted on the armature shaft 16 of the motor and meshing with a gear 17 90 mounted on a countershaft 18 which carries a worm 19 in mesh with the worm wheel 7, as shown in Fig. 1. Suitable bearings 20, 21 for the countershaft 18 are provided on the standard 5, as indicated by dotted lines in 95 Fig. 1.

Obviously it is necessary that the shaft 3 be held firmly against endwise movement ex-

cept when it is to be adjusted longitudinally, and the devices for so holding it and also for moving it endwise will now be described. As shown in Fig. 2, a housing 22 is provided which is secured to the standard 5 over the outer end of the bearing 4, and is provided with a bearing 23 in which is journaled the hub 24 of a worm wheel 25. This worm wheel is coaxial with the shaft 3, and its hub 24 is provided with a radial flange 26 forming a groove to receive the bearing 23 and prevent endwise movement of said worm wheel.

The hub 24 is internally screw-threaded and in it is fitted a screw 27 provided with a head 28 which abuts against the outer end of the shaft 3 and is connected therewith by a flanged ring 29 secured by screws 30. By this construction the shaft 3 is free to turn independently of the screw 27, but endwise movement of said screw correspondingly moves said shaft. The screw 27 is held against rotation by means of a cap 31 which is secured to the outer end of the housing 22 by screws 32, and is provided with a key 33 fitted in a keyway in the outer end of the screw, as shown in Fig. 2. By this construction, by rotating the worm wheel 25 the screw 27 will be caused to move endwise in one direction or the other, which motion will be communicated to the shaft 3, as above described, thereby similarly adjusting the roll supports carried by it, and consequently adjusting the margins of the web laterally. The worm wheel 25 is rotated by means of a worm 34 mounted on the armature shaft 35 of a reversible electric motor 36 supported by the standard 5, as best shown in Fig. 1. By this construction, whenever the operator wishes to adjust the margins of the rolls all he needs to do is to start the motor 36 in the proper direction, whereupon the shaft 3 will be moved endwise slowly, carrying the rolls with it. Instead of using a reversible motor any suitable reversing mechanism may be interposed between the motor and the worm. One end of the armature shaft 35 is preferably squared as shown in Fig. 1 so that in case of an emergency the worm may be rotated by the application of a crank thereto.

What I claim as my invention and desire to secure by Letters Patent, is—

1. A web roll stand comprising a longitudinally movable rotary shaft, a roll support mounted on said shaft and having means for supporting a plurality of rolls revolvably with reference to said shaft, bearings for said shaft, and means for moving said shaft longitudinally in said bearings to effect marginal adjustment of the roll or rolls carried by said roll support.

2. A web roll stand comprising a longitudinally movable rotary shaft, means mounted on said shaft for supporting a

plurality of rolls revolvably with reference to said shaft, bearings for said shaft, means for rotating said shaft, and means for moving said shaft longitudinally in said bearings independently of said rotating means. 70

3. A web roll stand comprising a longitudinally movable rotary shaft, means mounted on said shaft for supporting a plurality of rolls revolvably with reference to said shaft, a stationary standard having a bearing supporting one end of said shaft, means for moving said shaft longitudinally in said bearing to effect marginal adjustment of the rolls carried by said roll supporting means, and means mounted on said standard for rotating said shaft. 75

4. A web roll stand comprising a longitudinally movable rotary shaft, means mounted on said shaft for supporting a plurality of rolls revolvably with reference to said shaft, a standard having a bearing for one end of said shaft, a screw coaxial with said shaft and connected therewith, and means for moving said screw endwise for adjusting said shaft longitudinally in said 90 bearing.

5. A web roll stand comprising a longitudinally movable shaft, means mounted on said shaft for supporting a plurality of rolls revolvably with reference to said shaft, 95 a standard having a bearing, a worm wheel having a hub fitted in said bearing, said shaft being non-rotatably connected with said hub and movable endwise therethrough, a screw coaxial with said shaft and rotatably connected therewith, means for holding said screw against rotation, and means for moving said screw endwise. 100

6. A web roll stand comprising a longitudinally movable shaft, means mounted on 105 said shaft for supporting a plurality of rolls revolvably with reference to said shaft, a standard having a bearing, a worm wheel having a hub fitted in said bearing, said shaft being non-rotatably connected with 110 said hub and movable endwise therethrough, a screw coaxial with said shaft and rotatably connected therewith, means for holding said screw against rotation, a worm wheel mounted on said screw, and means for rotating said worm wheel to move said screw 115 endwise.

7. A web roll stand comprising a longitudinally movable shaft, means mounted on 120 said shaft for supporting a plurality of rolls revolvably with reference to said shaft, a standard having a bearing, a worm wheel having a hub fitted in said bearing, said shaft being non-rotatably connected with 125 said hub and movable endwise therethrough, a screw coaxial with said shaft and rotatably connected therewith, means for holding said screw against rotation, a worm wheel mounted on said screw, and a motor operatively connected with said worm wheel for 130

rotating the same to move said screw endwise.

8. A web roll stand comprising a longitudinally movable rotary shaft, means mounted on said shaft for supporting a plurality of rolls revolubly with reference to said shaft, a standard having a bearing for

said shaft, a screw mounted on said standard in coaxial alinement with said shaft and connected therewith, a motor mounted on 10 said standard, and means driven by said motor for moving said screw endwise to adjust said shaft longitudinally.
